SHUTTER AWNING

Henry C. Heiser, Parma, Ohio

Application June 27, 1940, Serial No. 342,741

8 Claims. (Cl. 20—59)

The invention relates generally to awnings and more particularly to awnings designed to remain in place over a window and the like and having a plurality of shutters or vanes which may be opened and closed as desired.

Shutter awnings should overlap throughout when closed in order to shed rain and exclude direct sunlight, and should open easily to admit air for ventilation and a desired degree of indirect light. From the standpoint of appearance, the space between the lowermost vane and the bottom frame member or valance should be equal to the spaces between the vanes when the awning is open, and the operating mechanism should project as little as possible behind the underside of the awning.

In prior shutter awning constructions the vanes have been mounted on lever arms pivoted intermediate their ends on a rigid frame member, with the free ends of the arms pivoted to a bar parallel to the frame member, providing a parallelogram movement mechanism for opening and closing the vanes.

With this type of mechanism the top vane cannot swing under the usual stationary vane or weatherstrip at the top of the awning if the vanes swing through approximately 90° to fully open position, which movement is desirable to admit a wide range of light and air. Consequently, it has been customary to notch out the rear edge of the top vane around the frame members to permit the remaining portion of said rear edge to extend behind the frame members and under the weatherstrip. The result is that when the awning is closed moisture can leak through the top vane where it is notched out around the frame members and tends to drip down close to the window which is covered by the awning.

Furthermore, with prior shutter awnings having a parallelogram movement mechanism, the space between the lowermost vane in fully open position and the cross frame member or valance at the bottom of the awning is substantially greater than the spaces between the vanes, presenting a more unsightly appearance than if the spaces were all equal.

The appearance of a shutter awning having a parallelogram movement mechanism is further marred when viewed in open position from the side or rear because the parallel bars and the vane supporting arms connected thereto extend out behind the frame members to a considerable extent.

Still another objection to prior shutter awnings having parallelogram movement mechanisms is

that since the vane supporting arms are pivoted on the rigid frame members, the pivots are necessarily spaced a substantial distance from the vanes to permit the vanes to swing clear of the frame members, with the result that opening operation becomes relatively difficult if the vanes have substantial length such as is required for wide windows, store fronts and the like.

It is a general object of the present invention to provide an improved shutter awning construction which overcomes all of the foregoing disadvantages.

More specifically it is an object of the present invention to provide a shutter awning having a novel and improved operating mechanism.

Another object is to provide a shutter awning in which all of the vanes closely overlap in closed position and swing through approximately 90° to fully open position.

Another object is to provide a shutter awning in which the space between the lowermost vane and the bottom frame member or valance is equal to the spaces between the vanes when the awning is open.

A further object is to provide a shutter awning which has a very easy opening action enabling the use of elongated shutter vanes.

Another object is to provide a shutter awning construction which is adapted for box-type awnings used with outwardly swinging casement windows and the like.

A further object is to provide a box-type awning having vanes in planes forming a dihedral angle, in which all of the vanes are disposed at the same angle when fully open.

A still further object is to provide an inexpensive and simply constructed shutter awning which is neat and attractive in appearance.

These and other objects are accomplished by the combinations, sub-combinations and arrangements of elements comprising the present invention, which is illustrated, described and claimed herein, and which generally includes laterally spaced frame members extending angularly downward from a support, operating bars slidable longitudinally in said frame members and having the ends of vane-supporting arms pivoted thereon at equal intervals, and links pivoted at one end to said frame members and at their other ends to said arms closely adjacent the undersides of the vanes carried thereby.

Referring to the drawings forming part hereof, in which preferred embodiments of the invention are shown by way of example.

Figure 1 is a vertical sectional view showing

one embodiment of the improved shutter awning applied to a window, the awning vanes being shown in closed position;

Fig. 2 is a similar fragmentary sectional view showing the shutter awning detached and the vanes in fully open position in full lines, and in partially open position in dot-dash lines;

Fig. 3 is a similar view showing a slightly different method of operating the shutter awning;

Fig. 4 is an elevation looking toward the rear side of an elongated shutter awning having a slightly different form of operating means, and showing the awning vanes in partly open position;

Fig. 5 is an enlarged fragmentary sectional view as on line 5-5, Fig. 4;

Fig. 6 is an enlarged fragmentary sectional view as on line 6-6, Fig. 4;

Fig. 7 is a fragmentary vertical sectional view similar to Fig. 1 showing another embodiment of the improved shutter awning with the vanes in closed position; and

Fig. 8 is an enlarged detached fragmentary sectional view thereof, showing the awning vanes in open position in full lines.

Similar numerals refer to similar parts throughout the drawings.

Referring first to Fig. 1 a preferred embodiment of the invention is shown applied to a conventional double sash window, having the upper sash 9 and the lower sash 10 vertically slidable in the window frame indicated generally at 11.

The improved shutter awning is indicated generally at 12 and includes rafter angles 13 secured at their upper ends to a laterally extending supporting angle 14 secured to the window frame 11 as by screws 15. Preferably, one flange or leg 16 of each rafter angle is disposed outwardly at right angles from the window as shown, and is bent angularly at its top end as shown at 17 for being secured to the lateral angle 14 as by rivets indicated at 18.

The number of rafter angles 13 may vary according to the lateral extent of the awning, but for an ordinary window, two laterally spaced rafter angles are used one at each side of the window.

The rafter angles 13 depend angularly downward and outward from the supporting angle 14, as shown, and are rigidly secured at their lower ends to the sides of the window frame by struts or braces 19, which may be twisted metal strips secured at their inner ends to the sides of the window frame as indicated at 20 and at their outer ends to the bottom ends of the rafter angles as indicated at 21.

The general construction thus far described is more or less conventional and well-known, and therefore forms no part of the present invention.

The novel shutter awning construction includes an actuating or operating bar 22 slidable in each rafter angle 13. Preferably, the bar 22 extends longitudinally in the rafter angle 13 and is slidably supported by the inner leg 23 thereof. A plurality of vane-supporting lever arms 24 is pivotally mounted at equal intervals on the actuating bars 22, the arms being pivoted at 25 on the bar at their inner ends and extending outwardly therefrom, and having angular flange portions 26 at their outer ends on which vanes 27 are mounted in overlapping relation with each other in closed position. These vanes may be of wood or metal as desired.

Each of the vane-supporting arms 24 has piv-

oted thereto a link 28, the link being pivoted at one end to the arm at a point 29 closely adjacent the underside of the vane supported by the arm and substantially below the top edge of the vane in closed position. The other end of the link is pivoted as at 30 to the leg or flange 16 of the rafter angle 13.

When the actuating bars 22 are moved downward longitudinally in the rafter angle 13, the pivots 25 move accordingly, and the vane-supporting arms and vanes pivot or swing outwardly about the pivots 29. The ends of the links 28 pivoted at 30 slidably restrain the actuating bars 22 from moving outwardly away from the legs 23 of the rafter angles and permit the actuating bars to move only longitudinally of the rafter angles, with the result that the pivots 29 move outwardly causing the links to swing outwardly about the pivots 30, as clearly shown in Fig. 2.

Means for moving the actuating bars 22 longitudinally of the angles may include a lever arm 31 pivoted at one end on one of the rafter angles, as at 32, and having a bent link 33 pivotally connected to the intermediate portion of the lever 31 at one end and to the operating bar 22 at its other end as indicated at 34. The free end of lever 31 may have a suitable cord or cable 35 attached thereto which conveniently may extend through a portion of the window frame, as indicated at 36, for being operated from inside of the window.

Due to the fact that the pivots 29 about which the vanes swing move outwardly away from the rafter angles as the vanes open, the vanes can be maintained in overlapping relation with each other in closed position and can swing through approximately 90° to fully open position, and the top vane when closed can fit closely under a stationary vane or weatherstrip 37 supported by the lateral angle 14 at the top of the shutter, without requiring any different mounting for the top vane or notching out of the rear edge thereof around the rafter angles.

Moreover, the bottom vane of the shutter awning can be made to overlap a horizontal frame member or valance indicated at 38 in closed position and the novel operating mechanism provides for a space between the bottom vane and the valance, when the vanes are fully open, equal to the spaces between the other vanes.

The improved shutter awning has a trim and pleasing appearance when viewed from the side or rear, because the operating mechanism is substantially all housed within the rafter angles or between the rafter angles and the vanes, so that with the exception of the operating lever 31 and link 33 there are no parts projecting rearwardly from the rafter angles.

The location of the pivots 29 closely adjacent to the underside of the vanes and below the rear edges of the vanes in closed position provides a leverage conducive to easily raising or lifting the weight of the vanes, making the opening operation of the awning relatively easy even though the vanes are elongated to cover large windows or store fronts.

The embodiment of the shutter awning shown in Fig. 3 is identical with that shown in Figs. 1 and 2, with the exception of the operating lever 31a which is pivoted intermediate its ends as at 39a on the rafter angle 13a, and is pivotally connected at its outer end to a link 40a which is in turn pivotally connected to one of the vanes 27a. In this embodiment when the inner end of the operating lever 31a is pulled downwardly the

other end of the lever 31a through the link 40a swings the vane 27a outwardly about pivot 29a, causing the actuating bar 22a to slide downwardly in the rafter angle and swing all of the vanes to open position.

The embodiment of the invention shown in Figs. 4, 5 and 6 is adapted for large windows or store fronts, and preferably utilizes elongated vanes 27b and more than two rafter angles 13b. Otherwise the construction of the shutter awning is identical with that shown in Figs. 1 and 2 with the exception that a slightly different type of operating lever construction is employed to take care of the added length and weight of the vanes.

As shown in Figs. 4 and 5 a square rocker shaft 41b is rotatably mounted in bearing brackets 42b on the underside of the rafter angles 13b and extends laterally across all of the rafter angles on which the awning is supported. An operating lever 43b is secured at its outer end to the rocker shaft 41b adjacent each bracket 42b and a curved link 44b is pivoted at one end on lever 43b intermediate the ends thereof and at its other end to the actuating bar 22b. Thus a downward pull on the free end of one of the levers 43b rotates rocker shaft 41b, and through the links 44b moves all of the actuating bars 22b longitudinally downward to swing the links 28b outward about pivots 30b and vanes 27b about pivots 29b, to the dot-dash position shown in Fig. 5.

Obviously, the curved links 44b can be connected through links similar to 40a in Fig. 3 to one of the vanes 27b to provide an operating mechanism similar to that shown in Fig. 3.

In Fig. 6 is shown a preferred way of attaching the weatherstrip 37b to the lateral supporting angle 14b by bolts 45b. The weatherstrip 37a in the embodiment of Fig. 3, and the weatherstrip 37 in the embodiment of Figs. 1 and 2 may be attached to the supporting angles in a similar fashion, as desired.

The embodiment of shutter awning shown in Figs. 7 and 8 is adapted for use with outwardly swinging casement windows and the like. As shown in Fig. 7 the shutter awning is secured to a laterally extending supporting angle 46c which is mounted on the building or window frame above the outwardly swinging window sash indicated at 47c. The rafter angles for this embodiment of shutter awning have angled portions 48c and 49c so that the rafter angles are outwardly convex, the angle portion 48c extending outwardly and preferably slightly downwardly from the supporting angle 46c, and the angled portion 49c extending angularly downward and slightly outward from the outer end of angle portion 48c.

One group of overlapping vanes 27c with their individual supporting lever arms 24c and links 28c is carried on the angled portion 48c, and another group of overlapping vanes 27c' with their individual lever arms 24c' and links 28c' is carried on the angled portion 49c, the vanes, lever arms and links being identical in construction with those in the embodiments of Figs. 1 to 5 inclusive. An actuating bar 50c is slidably mounted in the angled portion 48c for movement longitudinally thereof to open and close the group of vanes 27c carried by said angled portion, and a separate actuating bar 51c is slidably mounted in angled portion 49c for movement longitudinally thereof to actuate the vanes 27c' carried on that angled portion.

Means for operatively connecting the two 75

groups of vanes 27c and 27c' preferably comprises a connecting link 53c which is pivoted at its upper end to the upper actuating bar 50c, as at 54c. The lower end of the connecting link 53c is pivoted to one of the links 28c' mounted on the angled portion 49c, and preferably to the upper one of these links. The lower end of connecting link 53c, as shown, is pivoted to the link 28c' intermediate the ends thereof, so that when the actuating bar 51c moves downwardly to open the vanes 27c' carried by angled portion 49c to fully open position, the movement transmitted by connecting link 53c to actuating bar 50c is very slight in order that the vanes 27c carried by the angled portion 48c open a lesser amount than the vanes 27c'.

The connecting link 53c is preferably pivoted at its lower end to the uppermost link 28c' at a point 55c which is calculated to move the upper actuating bar 50c a distance which swings the upper vanes 27c to a fully open position in which said vanes are parallel to the lower vanes 27c' in their fully open position.

As shown, the lowermost vane 27c has a depending portion 56c secured to its forward edge for closing the space between said lowermost vane 27c and the uppermost vane 27c', when the vanes are in closed position.

The improved shutter awning is simple and inexpensive to construct, and has a neat and attractive appearance. With the improved vane opening and closing mechanism, the vane opening operation is relatively easy, even though the vanes are considerably elongated, and the vanes can be closely overlapped to be rainproof or swung through approximately 90° to a fully open position admitting a maximum amount of light and air.

I claim:

1. Shutter awning construction including a support, laterally spaced rafter angles secured at their upper ends to said support and depending angularly downward and outward therefrom, a bottom horizontal frame member extending between said angles, actuating bars slidably longitudinally in said angles, lever arms pivoted at their inner ends on said actuating bars at equal intervals longitudinally thereof, vanes mounted on the outer ends of said lever arms in overlapping relation with each other, a weatherstrip secured to said support overlapping the uppermost vane, links each pivoted at one end to one of said angles and slidably engaging said actuating bars and each link pivoted at its other end to one of said lever arms at points closely adjacent the vanes, and means for moving the actuating bars longitudinally of said angles to swing the vanes through substantially 90° to open position, the space between the lowermost vane in open position and the bottom frame member being equal to the spaces between the vanes.

2. Shutter awning construction including a support, laterally spaced rafter angles secured at their upper ends to said support and depending angularly downward and outward therefrom, actuating bars slidably longitudinally in said angles, lever arms pivoted at their inner ends on said actuating bars at equal intervals longitudinally thereof, vanes mounted on the outer ends of said lever arms in overlapping relation with each other, a weatherstrip secured to said support overlapping the uppermost vane, links each pivoted at one end to one of said angles and slidably engaging the actuating bar therein and pivoted at its other end to one of said vanes, and lever

means for moving the actuating bars longitudinally of said angles to swing the vanes through substantially 90° to open position.

3. Shutter awning construction including a support, laterally spaced frame members secured at their outer ends to said support and depending angularly downward and outward therefrom, actuating bars mounted on said frame members for movement longitudinally thereof, lever arms pivoted at their inner ends on said actuating bars, vanes mounted on said lever arms in overlapping relation with each other, links each pivoted at one end to one of said frame members and at its other end to one of said lever arms under the vanes closely adjacent their rear edges, each of said actuating bars being located between and slidably engaging an extension of a frame member and the links pivoted thereto.

4. Shutter awning construction including a support, laterally spaced frame members secured at their upper ends to said support and depending angularly downward and outward therefrom, actuating bars mounted on said frame members for movement longitudinally thereof, lever arms pivoted on said actuating bars, links each pivoted at one end to one of said frame members and at its other end to one of said lever arms, each of said actuating bars being located between and slidably engaging an extension of a frame member and the links pivoted thereto, vanes mounted on said lever arms in overlapping relation with each other when closed for swinging clear of the frame members through substantially 90° to fully open position, a weatherstrip secured to said support overlapping the uppermost vane in closed position, and lever means for moving the actuating bars to open and close the vanes.

5. In a shutter awning having a rafter angle, an actuating bar slideable longitudinally in said rafter angle, vane-supporting lever arms pivoted at their inner ends on said actuating bar, vanes mounted on said arms in overlapping relation with each other, links each pivoted at one end on said rafter angle and slidably engaging the actuating bar therein and pivoted at its other end on one of said lever arms at points closely adjacent to the rear edges of the vanes, and lever means mounted on the rafter angle for moving the actuating bar.

6. In a shutter awning having laterally spaced outwardly and downwardly directed frame members, a plurality of vane-supporting arms, vanes mounted on said arms in overlapping relation with each other, links each pivoted at one end to

one of said frame members and at its other end to one of said arms at points closely adjacent the rear edges of said vanes, and actuating bars slideable longitudinally of said frame members pivot-

5 ally connected with the inner ends of said arms for swinging them about their pivotal connections with the links, each of said actuating bars being located between and slidably engaging an extension of a frame member and the links pivoted thereto.

7. Shutter awning construction for outwardly swinging casement windows including a support, a rafter member secured at its upper end to said support and having angled portions extending 15 outwardly and then downwardly therefrom, an actuating bar mounted in each angled portion for movement longitudinally thereof, separate groups of lever arms pivoted at their inner ends at intervals on each of said bars, vanes mounted 20 on the outer ends of said lever arms of each group in overlapping relation with each other, links each pivoted at one end to one angled portion of said rafter member and as its other end to one of the arms of one group and links each pivoted at 25 one end to the other angled portion of said rafter member and at its other end to one of the arms of the other group, each of said actuating bars being located between and slidably engaging an extension of said rafter member and the links 30 pivoted thereto, and a connecting link pivoted at one end to the actuating bar for one group of lever arms and at the other end to one of the links for the other group of lever arms whereby the vanes of both groups are parallel in fully 35 open position.

8. In a shutter awning for outwardly swinging casement windows, a rafter member having outwardly and downwardly angled portions, an actuating bar movable longitudinally in each angled 40 portion, separate groups of vane-supporting lever arms pivoted individually on each of said bars, links each pivoted at one end to one rafter angled portion and at its other end to one of the arms of one group, and links each pivoted at one end 45 to the other rafter angled portion and to its other end to one of the arms of the other group, each of said actuating bars being located between and slidably engaging an extension of said rafter member and the links pivoted thereto, means operatively connecting said actuating bars and maintaining the lever arms of both groups parallel in fully open position, and means for moving one of said actuating bars.

HENRY C. HEISER.
